(57) **CLAIM**

The ornamental design for a wrist band attachment, as
shown and described.

DESCRIPTION

FIG. 1 is a perspective view of a first embodiment of a wrist
band attachment showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

FIG. 8 is another perspective view thereof wherein the end
piece of the attachment is in a turned position.

The broken lines illustrating the unclaimed portions of the
wrist band attachment form no part of the claimed design.
The dot-dash broken lines defining the boundaries of the
claimed design form no part of the claimed design.
